(57) **CLAIM**

I claim the ornamental design for an aircraft seat, as shown and described.

DESCRIPTION

FIG. 1 is a perspective view of an aircraft seat showing an embodiment of my new design;

FIG. 2 is a front view of the embodiment of FIG. 1;

FIG. 3 is a rear view of the embodiment of FIG. 1;

FIG. 4 is a right side view of the embodiment of FIG. 1;

FIG. 5 is a left side view of the embodiment of FIG. 1;

FIG. 6 is a top view of the embodiment of FIG. 1; and,

FIG. 7 is a bottom view of the embodiment of FIG. 1.

The broken lines in FIGS. 1-7 having a dash-dot configuration are for illustrative purposes only and form no part of the claimed design.
